UNITED STATES PATENT OFFICE.

JESSE F. JOHNSON, OF INDIANAPOLIS, INDIANA.

WHEEL-JACK.

SPECIFICATION forming part of Letters Patent No. 320,477, dated June 23, 1885.

Application filed April 8, 1885. (No model.)

To all whom it may concern

Be it known that I, JESSE F. JOHNSON, a resident of Indianapolis, Indiana, have made certain new and useful Improvements in Wheel-Jacks, a description of which is set forth in the following specification, reference being made to the accompanying drawings, in the several figures of which like letters indicate like parts.

10 My invention consists in the peculiar form of a jack-screw the base of which is adapted to rest upon the hub, the upper part of the screw carrying a yoke which provides a rest for the felly, for the purpose of raising the felly, so as to admit the removal of a battered 15 spoke without cutting the tire, and will be understood from the following description.

In the drawings, Figure 1 is a side view of my device, showing the spoke forced out of 20 line by means of the crank-screw, and a metal socket fixed upon the end of the spoke, the dotted lines indicating the normal position of the spoke when its head is entered into the socket and the pressure of the crank-screw 25 moved. Fig. 2 is a front view of my device, showing the projection formed on the base and top parts, to serve as guides for the spoke while being operated upon. Fig. 3 is a perspective view of the metal socket, and Fig. 4 30 is a longitudinal section of the same.

In detail, *b* is the cast-iron base, having at its upper end a threaded bore to receive the lower end of the right-and-left screw, *ls rs*, being the upper and right hand part of the 35 screw, which enters a threaded bore in the top of the jack, which is arranged to form a yoke having arms *y y'*, connected by a cross-bar, *cb*, the upper ends of the arms of the yoke having notches *n n*, which receive the 40 felly *f* and partially inclose it during the operation of the device. A ratchet-wheel, *rw*, is bolted to the central shank of the right-and-left screw, and pawls *pp* are pivoted on each 45 side, so as to engage alternately with the cogs of the ratchet-wheel *rw*.

h is a handle, which is intended to be inserted in the end of the case which carries the pawls, and *sl* is a slide held in place by a set-screw entering through a slot in the slide into 50 the butt of the ratchet-case. This slide is adapted to move either way, and to pass over the rear end of either one of the pawls, press-

ing that end down so as to free the other end of the pawl from engagement with the teeth of the ratchet-wheel. By this means either 55 one of the pawls may be thrown out of gear and the ratchet-wheel will turn freely in that direction, so that when the distance between the base and the top part of the jack is to be increased the ratchet is moved in one direction, 60 and when that distance is to be lessened it is to be moved in the other, and only the pawl on one side is to be used at a time, the opposite one being held down by the slide *sl*, which is moved so as to bind it at the rear 65 end. *cs* is a crank-screw passing through the cross-bar *cb* and having a swivel, *sw*, on its opposite end.

s is a metallic socket, which may be screwed 70 into the felly from the under side, or bolted through the felly and the tire, as desired, and the socket-opening is conformed to the shape and size of the spoke. It is frequently the case that the end of the spoke which enters the felly becomes battered and worn by constant use 75 and loose in the socket of the felly, and rattles, and heretofore, in order to remedy this difficulty, it has been found necessary to entirely remove the spoke and put in a new one, and as a consequence the tire has to be cut to allow 80 such change to be made.

My device is intended to avoid the necessity of cutting the tire or of changing the spoke, and it operates as follows: With a fine saw the spoke is cut through close to the under side of the felly, the jack is then applied, the base resting upon the hub, the ratchet turned so that the yoke is forced upward until the felly rests in the notches of the yoke-arms, the spoke being between them and between the guides *g* of the top and the base of the jack. By means of the crank-screw and its swivel, which fits against the side of the spoke, the spoke is forced out of line and out of the way, as shown in Fig. 1, after having 85 first been sawed through, so as to free it from the felly. A metal socket, *s*, is then fastened on the end of the spoke, as shown in Fig. 1, and the felly is then crowded up by means of the jack operated by the ratchet, until the 90 end of the spoke, which has in the meantime been suitably fitted to the size of the socket by a burning-iron or any convenient tool, with the socket attached, will pass under the 95

felly. The pressure of the crank-screw is now gradually removed, and the spoke will then resume its normal position. The felly is now lowered by a reverse movement of the screw 5 of the jack, and the operation is now completed by screwing the socket to the felly.

What I claim, and desire to secure by Letters Patent, is the following:

1. The wheel-jack herein described, comprising the right-and-left screw and base *b*, the yoke having arms *y y'*, notches *n n*, united by the cross-bar *cb*, the crank-screw *cs*, having swivel *sw*, and ratchet-wheel or nut connected with the right-and-left screw, with 15 means for operating the same, all combined substantially as described.

2. A wheel-jack having a suitable base, threaded to receive the lower portion of the right-and-left screw, a top piece threaded to 20 receive the upper portion of the same screw, and having one or more notches for the felly to rest in, in combination with a ratchet mechanism for operating the same, substantially as described.

25 3. A wheel-jack having a base and top adapted to be moved in opposite directions or drawn toward each other by suitable mechanism for operating a right-and-left screw entering the threaded openings in the top and

base, in combination with a screw mechanism 30 operating substantially at right angles to the lifting-screw, for pressing the spoke out of line, substantially as described.

4. A wheel-jack whose base is adapted to rest against the hub, its upper part to press 35 against the under side of the felly, the two connected by means of a right-and-left screw, and provided with guides for holding the spoke in place, and suitable mechanism for pressing the spoke out of line, all combined 40 substantially as described.

5. A wheel-jack having a base adapted to rest upon the hub of the wheel, and a top piece provided with arms for receiving the felly, the two connected by means of a right- 45 and-left screw, adapted to be operated in either direction by suitable ratchet mechanism having guides *g* on the top and base for partly inclosing the spoke, the crank-screw *cs*, provided with a swivel, *sw*, for forcing the spoke 50 out of line, all combined substantially as described.

In witness whereof I have hereunto set my hand this 15th day of January, 1885.

JESSE F. JOHNSON.
